UNITED STATES PATENT OFFICE.

BENJAMIN P. FORTIN, OF HARTFORD, CONNECTICUT, ASSIGNOR TO UNDERWOOD
TYPEWRITER COMPANY, OF NEW YORK, N. Y., A CORPORATION OF DELAWARE.

TYPE-WRITING MACHINE.

1,085,031.

Specification of Letters Patent. Patented Jan. 20, 1914.

Application filed May 18, 1912. Serial No. 698,093.

To all whom it may concern:

Be it known that I, BENJAMIN P. FORTIN, a citizen of the United States, residing in Hartford, in the county of Hartford and 5 State of Connecticut, have invented certain new and useful Improvements in Type-Writing Machines, of which the following is a specification.

This invention relates to typewriting machines, more particularly to the tabulating and column skipping devices arranged in machines of this character.

In machines such as the Underwood writing machine, tabulating devices have been 10 provided which comprise a set of denomination keys each operating a movable stop adapted to coöperate with adjustable stops of graduated lengths mounted upon a rack fixed to the carriage. Another set of column 15 skipping keys are provided which either operate another set of graduated stops or else operate cams which cause certain of the column stops on the carriage to be thrown out of operative position, so as to allow the 20 carriage to skip to the desired column.

The present invention has for its principal object to decrease the number of keys upon the keyboard of machines of the character above described. This is accomplished by 25 providing mechanism whereby certain of the denomination keys are converted into column skipping keys. The mechanism provided for this purpose is essentially as follows: Adjacent to one side of the row of 30 denomination keys are provided two additional keys. One of these keys, lettered "Column" is a master or controlling key which determines whether the denomination keys shall all act in their normal manner 35 or stopping at each column or whether certain of these keys shall act as column skipping keys. In the illustrated embodiment 40 of this invention the four middle denomination keys may be converted into column skipping keys. When the key lettered 45 "Column" is in raised position the denomination keys all act in their normal manner, and when this "column" key is depressed, the four middle denomination keys are con- 50 verted into column skipping keys to cause the carriage to skip to the first, second, third or fourth column, etc. The key lettered "Column release" operates to release the "column" key so as to allow it to rise, when

it is desired to cause the denomination keys 55 to revert to their normal function. This "column release" key releases the "column" key from its depressed position and allows it to rise by disengaging a spring catch from the "column" key, which spring catch snaps 60 on to the latter to hold it in position when depressed. When the "column" key is so depressed, it shifts out of position the rods which are connected to the denomination 65 keys and which normally actuate the movable denomination stops coöoperating with the column stops on the carriage. These rods are then in position to engage a slide having a series of stepped shoulders. The rods connected to the four denomination 70 keys, which are to be converted into column skipping keys, engage these shoulders, and raise the slide to different heights corresponding to the heights of the respective shoulders. Mounted upon this slide is a 75 column selecting stop, which is in position, when raised to engage the column stops on the carriage. As these column stops on the carriage are of different lengths, the carriage will be arrested at the desired column when 80 this stop of the length corresponding to that column hits the column selecting stop on the slide which has been raised to the required height.

Other features and advantages will here- 85 inafter appear.

In the accompanying drawings, Figure 1 is a fragmental elevation partly in section of an Underwood writing machine with my improvements applied thereto. Fig. 2 is a 90 diagrammatic plan illustrating the arrangement of keys, together with their connection to the movable stops. Fig. 3 is a view similar to Fig. 1, illustrating the position of the parts when the "column" key is in lowered 95 position and one of the column skipping keys is depressed. Fig. 4 is a perspective view illustrating the movable stops and the shifting slide in the position of parts shown in Fig. 1. Fig. 5 is a detail perspective 100 view illustrating the slide and column selecting stops raised to their extreme upward position. Fig. 6 is a detail perspective view illustrating the catch device for the "column" key, which catch is disengaged there- 105 from by the "column release" key.

The denomination keys 1 are mounted at the back portion of the keyboard and are

connected through levers 3, fulcrumed intermediate their ends on a fulcrum rod 4, to a series of vertical rods or bars 5. These bars when raised are normally adapted to 5 abut against shoulders 8 of denomination stops 7, and to raise the latter against the tension of springs 7^a so as to bring them in the path of travel of column stops 9 mounted on a rack 10 fixed to the carriage 11, indicated in dotted lines in Fig. 1. If when 10 the parts are in the position shown in Fig. 1, a denomination key is depressed, one of the denomination stops 7 will be raised and the carriage brought to a stop at the next column and at a point corresponding to the 15 proper denomination.

In accordance with the present invention, mechanism is provided whereby certain of the denomination keys are converted into 20 column-skipping keys. For this purpose a key 12 is provided adjacent to the denomination keys, and adapted when depressed to shift the rods 5 out of alignment with the denomination stops 7 and to bring these rods 25 into position to operate a column selecting stop. This key 12 is mounted on a vertical rod 13 connected to a lever 14 fulcrumed intermediate its ends on fulcrum rod 4 and the rear end of this lever engages an arm 30 15 projecting from a movable frame 16 fulcrumed at one end to a stationary part of the machine. This frame consists of two side bars 17 connected at their lower ends by a rod 18. Another rod 19 is connected 35 to these side bars at points intermediate their ends and extends through slots 20^a formed in the rods 5. When key 12 is depressed, frame 16 is rocked into the position shown in Fig. 3, swinging rods 5 out 40 of alignment with the denomination stops and, into operative relation with respect to the column selecting stop. The latter is mounted upon a slide 20 having at its lower end a series of stepped shoulders 21, 22, 23, 45 adapted to be engaged by projections 24 extending from certain of the rods 5 designated as 5^a, 5^b, 5^c, and 5^d. When the proper key is now depressed, the longest shoulder 21, is engaged by the projection on rod 5^a, 50 the slide is raised to its uppermost position, carrying with it the column selecting stop, and through the latter arresting the carriage at the first column. Similarly when certain other keys are depressed, shoulders 22 or 23, 55 or the plane bottom end of slide 20 are engaged and the column selecting stop raised so as to stop the carriage at the second, third or fourth column. In the drawings the four middle denomination keys are shown connected to rods 5^a, 5^b, etc., having the projections 24. Opposite these keys upon the keyboard appear the numerals 1, 2, 3 and 4, indicating the columns which the respective keys will select. It will be clear, however, 60 that any other of the denomination keys

may be so arranged and that any other of the rods 5 may be formed with projections to engage the slide 20.

The frame 16 is held normally in position so as to keep the rods 5 in operative relation with the denomination stops. This is accomplished by a pair of spring pressed plungers 25 mounted in the frame and acting against the side bars 17 adjacent to the rod 19. This normally keeps the arm 15 depressed and the key 12 raised. When it is desired to use the denomination keys only as column-skipping keys, it is desirable that the key 12 should stay down when depressed by the operator. For this purpose a catch 26 is provided. This is mounted on a rock shaft 27 to which is also fixed an arm 28 yieldably held inward by a spring 29 connected to the frame of the machine. This catch 26 has a cam face 26^a and a retaining face 26^b adapted to be engaged by a pin 30 mounted on rod 13 of the "column" key 12. When the latter is depressed, pin 30 engaging cam face 26^a forces the catch to one side and is then engaged by the retaining face 26^b and the key is thus held in depressed position. To allow the column key to rise after being thus held in depressed position, a key 31 lettered "Column release" is provided adjacent the "column" key. The key 31 is mounted on an arm 31^a provided with a pin 32 working against a cam face 33 extending from the arm 28 attached to the catch for the "column" key. When the "column release" key is depressed the pin 32 operating against the cam face 33, swings catch 26 out of engagement with the pin 30 on the rod 13, and the "column" key 12 is accordingly free to rise, which it will do owing to the downward pressure exerted on lever 14 by arm 15 of the spring pressed frame 16. To facilitate this raising of key 12 through the spring pressed rock frame as well as the retracting of the frame by the key, arm 15 is formed with a cam face 34 105 which engages a projection 35 formed on the end of lever 14.

The slide 20 is held in its lowered position by a spring 36 connected thereto and attached to any suitable point on the frame. 115 The column selecting counter stop mounted on this slide may be of any desired construction. Preferably this stop consists of a projection 37 carried by a rock arm 38 mounted on a vertical pivot in a bracket 39 120 fixed to the slide. On the other side of its pivot, arm 38 has attached or integral therewith an arm 39^a adapted to engage a projection 40 extending from a pivoted stop 41 mounted on a rock shaft 42, journaled in 125 bearings 43 fixed to the framework of the machine. A spring 44 (Fig. 2) normally tends to keep the stop 41 in raised position and out of the path of movement of the column stops on the carriage. When the 130

slide 20 is raised and the stop 37 is hit by a column stop on the carriage, rock arm 38 is swung, and through arm 39^a and the projection 40, the pivoted stop 41 is moved 5 against the tension of spring 44 until this stop is brought into the path of the column stop which latter is finally stopped thereby. The spring 44 serves as a buffer to cushion the blow given by the column stop and slow 10 down the carriage which is finally stopped by the comparatively rigidly constructed counter stop 41.

The usual universal bar 45 is pivoted adjacent to the rods 5, each of which rods when 15 raised, operates this bar through a projection 46 formed thereon. This universal bar is connected by a link 47 to an arm 48 fixed to a pin 48^a journaled in the framework. This pin projects from an arm 48^b carrying 20 at its end a roller 49 adapted to engage the bottom of the feed rack to disengage it from the escapement mechanism. A pinion 50 is also provided on this arm 48^b adjacent its end and engages the rack when arm 48 is 25 raised, operating the usual brake (not shown).

Variations may be resorted to within the scope of the invention, and portions of the improvements may be used without others. 30 Having thus described my invention, I claim:

1. In a tabulating mechanism for typewriting machines, a series of denomination keys, a series of denomination stops, push rods adapted to operate said stops, a column 35 selecting stop, and means for throwing certain of said push rods out of operative relation with the denomination stops and into operative relation with the column selecting 40 stop.

2. In a tabulating mechanism for typewriting machines, a series of denomination keys, a series of denomination stops, push rods adapted to operate said stops, a column 45 selecting stop, and means for throwing certain of said push rods out of operative relation with the denomination stops and into operative relation with the column selecting stop, said means comprising a movable arm 50 engaging said push rods, and means for actuating said arm.

3. In a tabulating mechanism, for typewriting machines, a series of denomination keys, a series of denomination stops, push rods adapted to operate said stops, a column 55 selecting stop, means for throwing certain of said push rods out of operative relation with the denomination stops and into operative relation with the column selecting stop, 60 said means comprising a swinging frame, a rod mounted in said frame and passing through slots formed in said push rods intermediate their ends, and means for swinging said frame.

4. In a tabulating mechanism for type-

writing machines, a series of denomination keys, a series of denomination stops, push rods adapted to operate said stops, a column selecting stop, and means for throwing certain of said push rods out of operative relation with the denomination stops and into operative relation with the column selecting stop, said means comprising a movable arm 70 engaging said push rods, means for actuating said arm, and yieldable means for 75 returning the same.

5. In a tabulating mechanism for typewriting machines, a series of denomination keys, a series of denomination stops, push rods adapted to operate said stops, a column 80 selecting stop, and means for throwing certain of said push rods out of operative relation with the denomination stops and into operative relation with the column selecting stop, said means comprising a swinging frame, a rod mounted in said frame and passing through slots formed in said push rods intermediate their ends, means for 85 swinging said frame, and a spring for returning the frame.

6. In a tabulating mechanism for typewriting machines, a series of denomination keys, a carriage, means operated by said keys for bringing the carriage to a stop at each column in position for the proper denomination, means including a key mounted on the 90 keyboard and adapted when depressed to convert certain of the denomination keys into column skipping keys, means for holding the last named key in depressed position until manually released, and a releasing device for said last-named key.

7. In a tabulating mechanism for typewriting machines, a series of denomination keys, a carriage, means operated by said keys 95 for bringing the carriage to a stop at each column in position for the proper denomination, means including a key mounted on the keyboard and adapted when depressed to convert certain of the denomination keys 100 into column skipping keys, means including a spring controlled catch for holding said key in depressed position, and a releasing key operative to release said catch.

8. In a tabulating mechanism for typewriting machines, a series of denomination keys, a carriage, means operated by said keys for bringing the carriage to a stop at each column in position for the proper denomination, means including a key mounted on the 115 keyboard and adapted when depressed to convert certain of the denomination keys into column skipping keys, means for holding the last named key in depressed position, and a key mounted adjacent said last mentioned key for releasing the latter so as to allow it to rise from its depressed position.

9. In a tabulating mechanism for typewriting machines, a series of denomination keys, a carriage, means operated by said keys 120

for bringing the carriage to a stop at each column in position for the proper denomination, means including a key mounted on the keyboard and adapted when depressed to convert certain of the denomination keys into column skipping keys, means including a spring controlled catch to hold said key depressed, and a key mounted adjacent said last mentioned key for releasing the latter so as to allow it to rise from its depressed position.

10. In a tabulating mechanism for type-writing machines, a series of denomination keys, a series of denomination stops, push rods operatively connected to said keys and arranged in alinement with said stops, and means for throwing certain of said rods out of alinement with said stops.

11. In a tabulating mechanism for type-writing machines, a series of denomination keys, a series of denomination stops, push rods operatively connected to said keys and arranged in alinement with said stops, said rods having projections extending therefrom, a column selecting stop, and means for throwing said rods out of alinement with said denomination stops and into position for the projections to coöperate with the column selecting stop.

12. In a tabulating mechanism for type-writing machines, a series of denomination keys, a series of denomination stops, push rods operatively connected to said keys and arranged in alinement with said stops, said rods having projections extending therefrom, a column selecting stop having a series of shoulders of graduated heights, and means for throwing said rods out of alinement with said denomination stops and into position for the projections to coöperate with the shoulders of the column selecting stop.

13. In a tabulating mechanism for type-writing machines, a series of denomination keys, a carriage, column stops mounted thereon, a series of denomination stops, push rods operatively connected to said keys and arranged in alinement with said denomination stops, a column selecting stop comprising a movable slide, a projection pivotally mounted on said slide, an arm fixed to said projection, an auxiliary stop operated by said arm when the projection is struck by one of said column stops, and means for throwing certain of said push rods out of alinement with the denomination stops and into position to operate said slide.

14. In a tabulating mechanism for type-writing machines, a series of denomination keys, a carriage, column stops mounted thereon, a series of denomination stops, push rods operatively connected to said keys and arranged in alinement with said denomination stops, a column selecting stop comprising a movable slide having a series of shoul-

ders of graduated heights, a projection pivotally mounted on said slide, an arm fixed to said projection, an auxiliary stop operated by said arm when the projection is struck by one of said column stops, and means for throwing certain of said push rods out of alinement with the denomination stops and into operative relation with respect to the shoulders on said slide.

15. In a tabulating mechanism for type-writing machines, a series of denomination keys, a carriage, column stops mounted thereon, a series of denomination stops, push rods operatively connected to said keys and arranged in alinement with said denomination stops, a column selecting stop comprising a movable slide, a projection pivotally mounted on said slide, an arm fixed to said projection, an auxiliary spring retracted step operated by said arm when the projection is struck by one of said column stops, and means for throwing certain of said push rods out of alinement with the denomination stops and into position to operate said slide.

16. In a tabulating mechanism for type-writing machines, a vertically movable slide having a series of stepped shoulders thereon, a column selecting stop on said slide, a series of push rods adapted to engage said shoulders, keys operatively connected to said push rods, denomination stops, and means to move said push rods alternatively into operative relation to the denomination stops and said slide.

17. In a tabulating mechanism for type-writing machines, the combination of a vertically movable slide having a series of stepped shoulders thereon, a column selecting stop on said slide, push rods adapted to engage said shoulders, keys operatively connected to said push rods, denomination stops, said push rods normally in operative relation to the denomination stops, an auxiliary key, and means operated by said auxiliary key to move certain of the push rods out of operative relation to the denomination stops and into position to coöperate with said slide.

18. In a tabulating mechanism for type-writing machines, the combination of a series of denomination keys, a series of denomination stops, push rods adapted to operate said stops, a column selecting stop, and means for throwing certain of said push rods out of operative relation to the denomination stops and into operative relation to the column selecting stop.

19. In a tabulating mechanism for type-writing machines, the combination of a series of denomination stops, denomination keys, power-transmitting elements between said keys and stops, a column selecting stop, and means to move certain of said elements out of operative relation to the denomination stops and into

operative relation with the column selecting stop.

20. In a tabulating mechanism for typewriting machines, the combination of a series of denomination keys, a series of denomination stops, a column selecting stop, push rods operatively connected to said keys and arranged in alinement with said denomination stops, and means for throwing certain of 10 said rods out of alinement with the denomination stops and into operative relation to the column selecting stop.

21. In a tabulating mechanism for typewriting machines, the combination of a series of denomination stops, a stationary frame in which said stops are slidably mounted, denomination keys, push rods forming an operating connection between the keys and denomination stops, a column 15 selecting stop, and means to move certain of said push rods out of operative relation to the denomination stops, and into operative relation to the column selecting stop.

22. In a tabulating mechanism for typewriting machines, the combination of a series of denominational stops, a stationary frame in which said stops are slidably mounted, denomination keys, push rods forming an operating connection between the keys and 25 denomination stops, a column selecting stop, an auxiliary key, and means operated thereby to move certain of said push rods out of the path of the denomination stops and into position to operate the column selecting 30 stop.

23. In a tabulating mechanism for typewriting machines, the combination of a series of vertically movable plunger stops, key levers, push rods supported thereon in alinement with the plunger stops and operable 40 when the keys are depressed to project said stops, a vertically movable member, a stop carried thereby, and means for swinging certain of said push rods into position to 45 operate said member and project said last-named stop when any one of said keys is depressed.

24. In a tabulating mechanism for typewriting machines, the combination of a series of vertically movable stops, key levers, push rods supported on said levers in alinement with the stops, a vertically slidable frame, a stop carried thereby, an auxiliary key lever, and means operated thereby to swing certain of 50 said push rods out of alinement with the stops and into position to operate said 55

slide when one of said first-named keys is depressed.

25. In a typewriting machine, the combination with a traveling carriage, column 60 stops thereon, a series of denomination stops vertically movable into the path of the column stops, denomination keys, operating connections between said keys and denomination stops comprising vertical push rods 65 in alinement with the denomination stops, a vertically slidable frame, a column-selecting stop carried thereby, said push rods having shoulders formed thereon, and means for swinging said push rods out of alinement with said denomination stops into a position with said shoulders beneath said 70 slidable frame.

26. In a typewriting machine, the combination of a traveling carriage, column 75 stops thereon, a series of vertically movable counter stops, key levers, push rods supported on said levers in alinement with the counter stops, means to swing the push rods out of alinement with the counter stops, and 80 means operable by certain of the push rods while out of alinement with the counter stops to cause the carriage to be brought to rest in positions corresponding to the operated push rod.

27. In a typewriting machine, the combination with a traveling carriage and column stops thereon, of counter stops, column selecting mechanism comprising push rods in operative relation to the counter stops, 90 and means to swing the push rods to an inoperative position relative to the counter stops, said column selecting mechanism operative to stop the carriage at any desired column position while said push rods are in 95 said inoperative position.

28. In a typewriting machine, the combination with a traveling carriage and column stops thereon, of counter stops, push rods in operative relation to the counter 100 stops, means to swing the push rods to an inoperative position relative to the counter stops, key levers to operate the push rods, and means including certain of said push rods and selectively operated by certain of the key levers to stop the carriage in column 105 positions corresponding to the operated key lever.

BENJAMIN P. FORTIN.
